EVAPORATOR VALVE MECHANISM

Franklin G. Slagel, Buffalo, N. Y., assignor to
 Fedders Manufacturing Company, Inc., Buffalo,
 N. Y., a corporation of New York

Application January 9, 1930, Serial No. 419,721

1 Claim. (Cl. 137—68)

This invention relates to refrigerating systems, and more particularly to mechanism for controlling the flow of refrigerant into the evaporator.

An object of the invention is to provide a refrigerant control mechanism which can be withdrawn as a unit from an evaporator sufficiently to detach and remove a valve member.

Another object of the invention is to provide a permanently sealed evaporator, of the flooded type, in which an automatically actuated refrigerant inlet flow control mechanism including a float can be partially withdrawn from the evaporator to inspect, service or replace the valve or its seat.

A still further object of this invention is to provide an evaporator for mechanical refrigerating systems in which the refrigerant inlet control mechanism is highly efficient in operation and of marked simplicity as a whole and in respect to its component parts, so that its manufacture is economically facilitated.

Other objects of the invention will appear from the following description taken in connection with the drawing, which forms a part of the specification, and in which:

Fig. 1 is a side elevational view, partially in section, of an evaporator and refrigerant inlet control mechanism therefor.

Fig. 2 is a fragmentary similar view with the valve control mechanism partially withdrawn from the evaporator.

Fig. 3 is a sectional view of the control mechanism taken on line 3—3 of Fig. 1.

Referring to the drawing by characters of reference, 10 represents generally an evaporator which forms part of a refrigerating system of the compressor-condenser-evaporator type. A closed vessel is employed to contain an accumulation of liquid refrigerant and oil, and in this instance comprises a sheet metal shell 11 having an open end permanently closed by the plate or wall 12, such vessel sections being secured together in leak proof relation.

An outlet tube 13 extends through the upper portion of the end wall 12 and is bent downwardly within the interior of the vessel. The end wall is provided with a hollow boss 14 for the reception of a cylindrical body 15 which supports the float and carries the valve and its seat, such body projecting through the end wall in close relation with the boss. In order to detachably secure the body to the wall, I provide it with a shoulder 16 which is engaged by the threaded cap 17 and pressed thereby tightly against a gasket 18 seated against the outer end of the boss,

the cap being screwed upon the boss for this purpose. A union 19 screws into the end of the body and establishes communication with the condenser (not shown).

The inner end of the body terminates in an arm 20 to which is pivotally connected the open float 21, a bracket 22 being fixed to the float and having a recess 23 into which the arm 20 extends, the arm being pivotally secured to the bracket by the pin 24. The pin 24 is secured in position by a cotter pin 25. Oil moving in cycle with the refrigerant will gradually creep over the open edges and into the float, and with the gasified refrigerant is removed through the outlet tube 13 which extends into the float and leads to the compressor (not shown), suction by the compressor causing such removal.

The body 15 is also provided with a passage 26 extending axially therethrough, and a removable valve member seat 27 having a restricted passage 28 therethrough is screwed into the body passage from the exterior end thereof. A passage 26' in the body provides an outlet from the passage 26 to the interior of the vessel. A needle valve 29 projects into the passage 26 through the inner end of the body, and is reciprocably associated with the inner end of the seat member 27 to control the passage of refrigerant through the body, the valve extending into the bracket recess 23 and being pivotally secured by the detachable pin 30 which extends through the bracket and is secured by the cotter pin 31.

The inner end wall of the valve member 27 is formed as a circular edge 33 which is pressed tightly against the shoulder 34 within the body to provide a leak proof contact, thus eliminating the necessity of a gasket or other form of metallic sealing means. The outer end of the valve seat member is formed with suitable recesses into which a tool can be inserted to screw it into or from the body.

As the accumulation of liquid refrigerant in the vessel falls, the float likewise moves therewith and moves the valve away from the seat, allowing refrigerant to flow into the vessel through the passage 26'. The float rises with the accumulation level and moves the valve to close the passage through the seat, thus shutting off the inflow of the refrigerant to the vessel. The valve fit in the arm, or the fit of the pin 30 is such that reciprocation of the valve during pivotal movement of the float can result, such float movement being small between the open and closed positions.

The float bracket is small enough to be drawn

partially through the opening in the boss 14, and when the cap 17 is unscrewed the body, together with a portion of the float bracket can be pulled exteriorly of the vessel wall. Such withdrawal allows inspection or removal of the needle valve from the exterior of the evaporator. It also permits removal of either or both of the pins 24 and 30 so that the valve or the body 15 can be removed and serviced or replaced. Furthermore, it will be seen that removal of the coupling 19 will permit removal of the valve seat from the body, either when assembled or removed from the vessel wall.

The delicacy of the refrigerant inlet control mechanism is well known and the structure described affords a quick and inexpensive servicing or replacement of parts thereof from the exterior of the vessel without removal of a wall section.

Although this invention has been described in connection with certain specific embodiment, the principles involved are susceptible to numerous

other applications which will readily occur to persons skilled in the art, and the invention is therefore to be limited only as indicated by the scope of the appended claim.

What I claim is:

In an evaporator for refrigerating systems, a vessel for containing liquid refrigerant having a sealed end wall with an opening therethrough, a withdrawable body extending through the opening in the wall of the vessel, said body having a refrigerant inlet passage extending therethrough, a float in the vessel having a reduced bracket portion pivoted to the inner end of the body and partially removable therewith through the wall opening to a position exterior of the vessel permitting detachment of the body therefrom, and valve means detachably associated with the reduced bracket portion of the float and the body for controlling refrigerant flow through the body, and a single detachable means for fixing the body in leak-proof relation with the vessel wall.

FRANKLIN G. SLAGEL.
